UNITED STATES PATENT OFFICE.

JOHN E. HOY, OF MIDLAND, MICHIGAN, ASSIGNOR OF ONE-HALF TO JEFFERY N. COLLINS, OF DETROIT, MICHIGAN, AND ONE-HALF TO CARL C. HOUSE, OF MIDLAND, MICHIGAN.

DESIGN FOR A TOY GUN.

56,615.

Specification for Design. Patented Nov. 16, 1920.

Application filed May 24, 1920. Serial No. 383,998. Term of patent 14 years.

To all whom it may concern:

Be it known that I, JOHN E. HOY, a citizen of the United States, residing at Midland, in the county of Midland and State of Michigan, have invented a new, original, and ornamental Design for a Toy Gun, of which the following is a specification, reference being had to the accompanying drawing, forming part thereof.

Figure 1 is a side elevation of the toy gun. Fig. 2 is a side elevation of the reverse side.

I claim:

The ornamental design for a toy gun as shown.

JOHN E. HOY.
